J. S. HUNTOON

CRIBBING

Filed May 27, 1922.

UNITED STATES PATENT OFFICE.

JOHN S. HUNTOON, OF DETROIT, MICHIGAN, ASSIGNOR TO MASSEY CONCRETE PRODUCTS CORPORATION, OF CHICAGO, ILLINOIS, A CORPORATION OF VIRGINIA.

CRIBBING.

Application filed May 27, 1922. Serial No. 564,082.

To all whom it may concern:
Be it known that I, JOHN S. HUNTOON, a citizen of the United States, and resident of Detroit, in the county of Wayne and State of Michigan, have invented certain new and useful Improvements in Cribbing, of which the following is a full, clear, concise, and exact description, reference being had to the accompanying drawings, forming a part of this specification.

This invention relates to improved cribbing for use in constructing retaining walls such as used in connection with fills and embankments of railways.

15 The cribbing of the present invention consists of few dissimilar parts and may be manufactured at a central point and transported to the position where the retaining wall is to be constructed, and the construction of the retaining wall may be accomplished by a minimum number of relatively unskilled workmen.

In the embodiment of the invention disclosed in the present application, but two 25 different types of strips or slabs are employed, all of the headers or anchor slabs being alike, and all of the stretchers or facer slabs being alike. In the construction of the retaining wall, the headers are arranged 30 in substantially parallel tiers at right angles to the longitudinal axis of the wall, and the stretchers are arranged in tiers at substantially right angles to the headers, a tier of stretchers being provided adjacent to each end of the headers. In constructing 35 the retaining wall, the strips or slabs are placed one upon another as a rail fence or pen, having but a single rail on a side, would be constructed. In other words, the headers will be supported upon the stretchers, one at each end, and the stretchers in turn 40 will be supported upon the ends of the headers. This arrangement permits the retaining wall to be constructed by a minimum 45 number of men—in fact, the wall may be constructed by one man if the individual slabs are of a size to be readily handled by one man.

50 In the drawings, Figure 1 is a face view of a portion of a wall with the ends of certain of the headers being broken away to show the abutting relation of the stretchers;

Figure 2 is a vertical section through a

wall adjacent to one of the tiers of headers; 55 Figure 3 is a side view of one of the individual header slabs;

Figure 4 is a section substantially on the line 4—4 of Figure 3;

Figure 5 is a section substantially on the 60 line 5—5 of Figure 4;

Figure 6 is a sectional view of one of the stretcher strips showing the location of the reinforcing rods therein, and

Figure 7 is a section on the line 7—7 of 65 Figure 6.

Referring now to the drawings, in which like reference characters indicate like parts in the several views, 10 indicates a header and 11 a stretcher. The headers 10—10 are 70 arranged in substantially vertically extending tiers parallel to each other, and the stretchers 11—11 are arranged in tiers, there being one tier of the stretchers adjacent to each end of the headers 10.

75 The headers 10 are formed at each end with oppositely disposed flanges 12, so that the extremity of the header is substantially T-shaped. Extending throughout the length of the header 10 is a plurality of reinforcing rods 13, one of the rods 13 being positioned adjacent to each corner of the header. It should be noted that the stretchers and headers will preferably be formed of concrete, or similar material, as is usual in 80 structures of this character. The rods 13 adjacent to the ends of the header will be extended at right angles and into the flanges 12. This structure is clearly disclosed in 85 Figure 4 of the drawings. The stretcher 90 slabs 11 are similarly reinforced, each having a plurality of rods 14 imbedded therein and extending longitudinally thereof. These rods, as shown in Figure 7, are positioned, one adjacent to each corner of the 95 slab, and the ends thereof are turned at right angles, as shown in Figure 6, so that the reinforcing rods may be anchored at their ends within the stretcher slab.

In constructing the retaining wall, the 100 headers 10 are disposed with the flanges 12 extending in a vertical direction, and an end of one of the stretcher slabs 11 is disposed between each one of the headers 10 and the next adjacent one.

105 Referring now to Figure 2, it will be noted that beginning at the bottom, the stretcher slabs 11 are disposed below the

lowermost header bar 10. These will preferably be so arranged that the one at the right is slightly lower than the two at the left so that the face of the wall will be slightly rearwardly inclined. The lowermost header bar is positioned upon the lowermost stretchers 11 with the flanges 12 thereof projecting downwardly immediately adjacent to the outer edges of the stretcher slabs. A plurality of header bars 10 is arranged in substantially the same plane and spaced apart horizontally distances substantially equal to the length of the stretcher slabs 11. The stretcher slabs 11 are then placed upon the header bars, one at each end immediately adjacent to the inner sides of the flanges 12. Except at the ends of the wall, the slabs 11 are arranged with their adjacent ends abutting substantially over the central longitudinal axis of the supporting header bar. Another course of headers 10 will then be placed upon the stretchers 11. This process of placing the headers 10 on the stretchers 11, and then a course of stretchers 11 on the headers 10, will be repeated until the desired height of wall is obtained.

Where the retaining wall is of considerable height, say over ten or twelve feet, a secondary or supplemental course of headers and another course of stretchers may be added, as indicated at the right in Figure 2. The headers of the rear course will preferably be arranged immediately adjacent to the headers of the forward course with the ends sufficiently overlapping so that the stretchers 11 at the rear of the first course of headers may be positioned between the flanges 12 at the rear ends of the headers of the first course and the flanges 12 at the forward ends of the headers of the second course. The rear ends of the headers of the second course alternate with stretchers, as clearly shown in Figure 2.

In case an exceptionally high retaining wall is to be constructed, it may be desirable to provide a third or even a fourth course of the headers, each of which will bear the same relation to the preceding course as the course at the right in Figure 2 bears to the course at the left. It is to be understood, of course, that each succeeding supplemental course of headers will usually be of less height than the preceding course. The supplemental courses of headers and the stretchers associated therewith act to anchor the forward course and prevent the pressure of the dirt or other substance back of the wall from forcing the wall out of position.

It is, of course, to be understood that after the retaining wall has been built, the spaces in and about the headers and stretchers will be filled with dirt or other substance, as is usual with arrangements of this character.

The fact that the stretchers are positioned

back of the flanges 12 on the headers acts to maintain the stretchers in position, and the arrangement of the stretchers on the headers and the headers in turn on the stretchers acts, by means of frictional contact, to firmly bind the whole structure together. Furthermore, this arrangement requires the use of but two types of slabs, the header slabs, as previously described being T-shaped at each end, and the stretcher slabs being uniform throughout their length and either square or rectangular in cross section. The interlocking relation of the forward ends of the header bars of the rear course with the forward face of the adjacent stretcher slabs firmly anchors the rear course to the forward course. With the present arrangement, it is obvious that the greater the weight brought to bear on the several slabs forming the retaining wall, the more firmly they become locked together.

While in the drawings and in the preceding description, the disclosure has been limited to certain definite details, it is to be understood that applicant contemplates certain departures from the specific details disclosed and the invention, therefore, is to be limited merely by the scope of the appended claims.

Having thus described my invention, what I claim as new and desire to secure by Letters Patent of the United States is:

1. A retaining wall having a vertical tier of stretchers of constant rectangular cross section throughout, a vertical tier of headers alternating with the stretchers and disposed at right angles thereto and provided with T heads lapping and projecting beyond the respective adjacent upper and lower stretchers at one side of the tier of stretchers, and a second vertical tier of headers parallel with the first tier of headers and in the same respective horizontal planes therewith and projecting at the opposite side of the tier of stretchers, each of said second headers having an end portion lying between successive stretchers and provided with a T head lapping and projecting beyond said successive stretchers at the side of the tier opposite the heads of the first mentioned headers.

2. A retaining wall comprising two vertical parallel tiers of substantially horizontal headers, the adjacent heads of the two tiers being overlapped horizontally, the overlapped ends having T heads, and a vertical tier of substantially horizontal stretchers of constant rectangular section throughout alternating with the headers and disposed at substantially right angles thereto and lying between and engaged by the T heads of the respective adjacent upper and lower headers and projecting beyond said stretchers.

3. A retaining wall comprising two spaced vertical tiers of substantially hori-

zontal and parallel stretchers of constant rectangular cross section throughout, a vertical tier of headers alternating with the stretchers and extending across and between the same at substantially right angles thereto, each header being provided at each end with a T head lapping and projecting beyond the adjacent upper and lower stretchers at the outer sides thereof, a third vertical tier of stretchers in parallelism with the first mentioned tier of stretchers, and a second vertical tier of headers parallel with the first mentioned headers and extending transversely between the successive members 10 of the third tier of stretchers and also one of the first mentioned tier of stretchers, each of said headers having a T head at each end thereof lapping and projecting beyond the adjacent upper and lower stretchers, the 15 heads at the outer ends of said headers lying at the outer side of the third tier of stretchers, and the heads at the other ends 20

of the said headers lying at the inner sides of the adjacent tier of stretchers.

4. In a retaining wall, spaced parallel 25 stretchers of constant cross section throughout, a header lying upon the stretchers transversely thereof and provided at each end with a vertically disposed T head having its lower portion engaging the outer face 30 of the adjacent stretcher and projecting beyond said face, and another pair of parallel stretchers parallel with the first mentioned stretchers and lying upon the top of the header and against the inner faces of 35 the upper portions of the respective heads of the headers, and similarly engaged.

In witness whereof, I hereunto subscribe my name this 19th day of May, 1922.

JOHN S. HUNTOON.
